Application April 22, 1942, Serial No. 440,078

7 Claims. (Cl. 280—11.13)

This invention relates to improvements in that type of multi-layer or laminated ski in which one or more preformed, tapered layers or laminations are embodied to produce a ski whose end portions are relatively thin and flexible as compared with the middle portion. The object of the invention is to provide an improved ski of this type in which the construction of the tapered layers or laminations is such that the strength, warpage resistance and swing retaining characteristics are substantially enhanced as compared with similar skis produced by conventional methods of manufacture.

Two-layer skis have been made with a thin, full length bottom layer of uniform thickness from end to end and a relatively thick, full length top layer which is tapered so that its end portions are relatively thin and flexible compared with its middle portion. Such skis are weakened during the process of manufacture by reason of the fact that the thickness and bending resistance of the top layer requires the application of a heavy molding or bending pressure to give the laminated ski the required longitudinal curvature and camber. This heavy pressure, in overcoming the bending resistance of the relatively thick top layer, causes the wood fibres of said layer to be crushed and otherwise damaged so that this layer loses much of its original strength and flexibility during the bending operations. Another objection to the two-layer ski mentioned herein is that, owing to the great disparity between the thickness of the bottom layer and the thickness of the top layer, the bottom layer is too weak to prevent warpage of the ski due to the internal working and twisting tendency of the relatively stronger top layer.

Three-layer skis have been made with a tapered central layer or core locked in place between relatively thin and longer top and bottom layers which are of substantially uniform thickness from end to end. In this case the front and rear end portions of the full length top and bottom layers are directly joined together beyond the corresponding ends of the central or core layer which is tapered so that it decreases in thickness from its middle toward its end portions. This type of three-layer ski is subject to breakage at or adjacent the thin ends of the central or core layer. It is also open to the objection that the two-layer end portions thereof do not long retain their original curvature and are easily warped.

According to the present invention all the foregoing objections are eliminated by the improved multi-layer ski constructions which will now be

described with reference to the accompanying drawings, in which—

Figure 1 is a side elevation of a two-layer ski embodying my invention.

5 Figure 2 is a side elevation of a three-layer ski.

Figure 3 is a side elevation of a four-layer ski.

10 Figure 4 is an enlarged transverse sectional view taken substantially along the line 4—4 of Fig. 3.

Figure 5 is a view similar to Fig. 4 but showing a modified type of four-layer ski.

15 Figure 6 is a view similar to Figs. 4 and 5 but showing a five-layer ski.

Figure 7 is a side elevation of a six-layer ski.

Figure 8 is a side elevation of a modified form of six-layer ski.

20 Figure 9 is a side elevation showing a further type of four-layer ski.

Figure 10 is an enlarged transverse sectional view taken substantially along the line 10—10 of Fig. 9.

25 Figure 11 is an enlarged transverse sectional view taken substantially along the line 11—11 of Fig. 9.

The two-layer ski shown in Fig. 1 comprises full length tapered layers 5 and 6 of duplicate construction. These layers are preformed so that they gradually decrease in thickness from the middle toward the end portions thereof. They are, insofar as it is practicable to make them so with present manufacturing methods, exact duplicates as regards length, width and thickness.

30 As regards the thickness characteristics, it is highly important that the thickness of the top layer 5 at any given point along the entire length of the ski shall be the same as the thickness of the bottom layer 6 at the same point. This equalization of the thickness of the two layers at all corresponding points along the length of the ski produces an improved laminated construction in which the strength and thick-

35 ness and, consequently, the magnitude of the internal working and twisting tendency of one layer at any given point along the length of the ski is exactly counterbalanced by the strength, thickness and magnitude of the internal working and twisting tendency of the companion layer at

40 the same point in all cases in which the two layers are made of wood of equal strength characteristics. This permits the two layers to be assembled so that, in the finished ski, the internal working and twisting tendency of one layer which

45 tends to cause warpage is opposed and neutralized.

by the internal working and twisting tendency of the companion layer at all points along the length of the ski. It is not necessary that the two layers be made of wood having exactly the same weight characteristics but it is important that the wood used in both layers should be uniform as regards strength and internal working or warping characteristics.

The ends of the finished ski shown in Fig. 1 are thickened and strengthened by toe and heel shaping wedges 7 and 8 interposed between the layers 5 and 6. These wedges are formed and fitted in place so that the grain thereof is at right angles to the grain of the layers 5 and 6. It may be noted here that all the component parts of the ski, comprising the layers 5 and 6 and the shaping wedges 7 and 8 are firmly joined together by conventional gluing and pressing operations. The layers 5 and 6 may be of one piece construction or, alternately, either or both of them may be composed of narrow lengthwise extending strips or rails glued together in side by side relation.

Another advantage of the ski shown in Fig. 1 is that its swing retaining characteristics are substantially improved by reason of the fact that both layers have practically the same longitudinal curvature and are of equal thickness at all corresponding points along the length thereof. In skis where there is substantial variation in the length and curvature of component layers or in the thickness of such layers at corresponding points along the length of the ski, the swing characteristics of the ski, as a whole, is impaired by the lack of uniformity of the swing retaining characteristics of the component layers as compared with each other. It is also true that the best results, as regards warpage resistance and swing retaining characteristics, are not obtained in multi-layer skis in which there is considerable disparity between the strength and thickness of corresponding portions of the layers forming the thinner or end portions of the complete ski.

A further advantage to be noted in connection with the ski shown in Fig. 1 is that the top and bottom layers are substantially thinner than the single tapered top layer of the previously mentioned conventional two-layer ski and may, therefore, be bent to the required longitudinal curvature or camber by the application of considerably less bending pressure and with less damage to the fibres of the wood.

In Fig. 2 I have shown a modified form of ski composed of three full length layers including a top layer 10, an intermediate layer 11 and a bottom or runner layer 12. The layers 10 and 11 are made in exactly the same way as the previously mentioned layers 5 and 6, except that they are made thinner at all corresponding points along their length so that the addition of the third or runner layer 12 produces a three layer ski which has the same overall thickness as the two layer ski shown in Fig. 1. In this connection it will be understood that the overall thickness of the three layer ski shown in Fig. 2 has been exaggerated to permit a clearer showing of the component layers. The bottom or runner layer 12 shown in Fig. 2 is preferably of uniform thickness from end to end and is relatively thin compared to the thicker portions of the associated layers 10 and 11, the thickness of the layer 12 being preferably the same as that of the thinnest portions of the tapered layers 10 and 11. In this case the disparity between the thickness of the bottom or runner layer 12

and the thickness of the thicker portions of the superimposed taper shaping layers 10 and 11 is of no consequence since the layers 10 and 11 provide a non-warped body portion which is effective to prevent any warping of the weaker runner layer 12. The swing retaining and warpage resistance characteristics of the three layer ski shown in Fig. 2 are controlled entirely by the construction of the main body forming layers 10 and 11 and are not adversely affected by the difference in thickness between these layers and the bottom or runner layer 12. Consequently, the three layer ski shown in Fig. 2 has the same improved swing retaining characteristics as the two layer ski shown in Fig. 1. As regards strength and warpage resistance characteristics, the three layer ski shown in Fig. 2 is superior to the two layer ski shown in Fig. 1. This is due to the fact that, in the three layer ski, the tapered layers employed are thinner than those employed in the two layer ski and therefore may be bent to the required longitudinal curvature or camber with less pressure and with less danger of damaging the wood fibres. It may also be noted here that the division of the total thickness of the ski between three layers instead of between two layers provides a generally stronger construction which is more resistant to warpage. It may also be pointed out here that, in a ski composed of three full length layers, the thinner or end portions of the ski tend to retain their original curvature to a much greater extent as compared with the end portions of skis made only of two superimposed layers.

Each of the component layers of the ski shown in Fig. 2 may be of one piece construction, or alternatively, may be composed of narrow longitudinally extending strips or rails glued together in side by side relation. In this connection it will be understood that one or more layers may be of one piece construction and the remaining layer or layers made of narrow strips or rails glued together in side by side relation.

In Figs. 3 and 4 I have shown a four layer ski comprising two full length tapered layers 15 and 16 of duplicate construction and two full length non-tapered layers 17 and 18. In this case the layers 15 and 16 are tapered in the same manner as described in connection with the tapered layers of Figs. 1 and 2 but are separated from each other by the interposition of the non-tapered layer 17. The layers 17 and 18 are of uniform thickness from end to end and are substantially thinner than the thicker portions of the tapered layers 15 and 16. The layers 17 and 18 are also preferably of equal thickness as compared with each other.

Another important feature of the four layer ski shown in Figs. 3 and 4 is that each of the layers 15 and 16 is composed of narrow strips or rails glued together in side by side relation while each of the layers 17 and 18 is of one piece construction. This provides a well balanced laminated ski which has improved swing retaining characteristics and is not easily warped. In this connection, it is particularly important that, in the thinner portions of the skis, solid or one piece layers be interposed between and secured to those layers which are composed of rails glued together in side by side relation. This arrangement of the layers is resistant to both transverse and longitudinal curvature or warpage.

In Fig. 5 I have shown a further example of a four layer ski embodying the principles of my

invention. In this case the top and bottom layers 20 and 21 are of uniform thickness from end to end and are relatively thin compared with the thicker portions of the duplicate intermediate layers 22 and 23 which are tapered so that they gradually decrease in thickness from the middle toward the end portions thereof. Each of the top and bottom layers 20 and 21 is of one piece construction while the intermediate layers 22 and 23 are each composed of a plurality of narrow strips or rails glued together in side by side relation.

In Fig. 6 I have shown a five layer ski in which the top layer 25, the central layer 26 and the bottom or runner layer 27 are of uniform thickness from end to end and are relatively thin compared with the thicker portions of the remaining layers 28 and 29 which are tapered so that they decrease in thickness from the middle toward the end portions thereof. In this case the tapered layers 28 and 29 are of duplicate construction and are each composed of a series of narrow strips or rails glued together in side by side relation, the upper tapered layer 28 being sandwiched between the top layer 25 and the central layer 26 and the lower tapered layer 29 being sandwiched between the central layer 26 and the bottom or runner layer 27.

In connection with the skis shown in Figs. 5 and 6 it will be understood that all the component layers extend the full length of the ski so that the end portions of the ski will have the same number of laminations or layers as the central portion.

In Fig. 7 I have shown a six layer ski which comprises five full length tapered layers 30, 31, 32, 33 and 34 of duplicate construction and a single full length bottom layer 35 which is of uniform thickness from end to end and is relatively thin compared with the thicker portions of the tapered layers.

In Fig. 8 I have shown a further type of six layer ski which comprises three full length tapered layers 37, 38 and 39 of duplicate construction and three full length non-tapered layers 40, 41 and 42. The three last mentioned layers are of uniform thickness from end to end and are relatively thin compared to the thicker portions of the tapered layers. In this case the tapered and non-tapered layers are alternately arranged so that the tapered layer 37 forms the top layer while the non-tapered layer 42 forms the bottom or runner layer, the nontapered layer 40 being interposed between the two tapered layers 37 and 38 and the nontapered layer 41 being interposed between the tapered layers 38 and 39. In the case of the six layer ski shown in Fig. 8 an exceedingly good construction is obtained by forming each tapered layer so that it consists of narrow strips or rails glued together in side by side relation, the remaining or non-tapered layers being of one piece construction. However, it will be understood that, with reference to all of the different types of skis described herein, certain component layers may be of one piece construction and the remaining layer or layers composed of narrow strips or rails glued together in side by side relation. In all cases, however, it is essential that the tapered layers be of equal thickness at all corresponding points along the length thereof.

In Figs. 9 to 11 inclusive I have shown a further type of ski comprising four superimposed layers designated 44, 45, 46 and 47. The two upper layers 44 and 45 are tapered so that they grad-

ually decrease in thickness from the middle toward the end portions thereof, these layers being of equal thickness at corresponding points along the length thereof. The layer 46 is thinner than the thicker portions of the layers 44 and 45 but is somewhat thicker than the bottom layer 47. The layers 44 and 46 are composed of rails glued together in side by side relation whereas the layers 45 and 47 are of solid construction. It will be noted that at the end or thin portions of the ski the thickness of the layer 46 is somewhat greater than the thickness of each of the layers 44, 45 and 47 at the same portions of the ski. This provides a very desirable type of ski in which the layers 44 and 46, being composed of rails glued together in side by side relation, have little tendency to warp and serve to prevent warping of the layers 45 and 47 at the end or thin portions of the ski where warpage is most likely to occur. The layers 45 and 47, being of solid construction, tend to support the layers 44 and 46 against the rolling or curving action which is characteristic of skis in which certain layers are composed of rails glued together in side by side relation.

Having thus described my invention, what I claim is:

1. A laminated ski including a plurality of superimposed full length tapered layers forming the main or body portion of the ski and one or more full length runner layers secured to the bottom surface of the lowermost of the body forming layers, said runner layer or layers being of uniform thickness from end to end and being relatively thin compared with the thicker portions of the tapered body forming layers, said ski being further characterized in that the body forming layers are of equal thickness at any given point along the length of the ski.
2. A three layer laminated ski in which all the layers extend the full length of the ski, the top and intermediate layers being tapered so that they gradually decrease in thickness from the middle toward the end portions thereof and the bottom or runner layer being of uniform thickness from end to end and being relatively thin compared with the thicker portions of the tapered layers, said ski being further characterized in that the thickness of each tapered layer, as measured at any given point along the length of the ski, is substantially exactly equal to the thickness of the companion tapered layer as measured at the same point along the length of the ski.
3. A four layer laminated ski comprising two full length tapered layers alternately arranged with respect to two full length non-tapered layers, said tapered layers being of gradually decreasing thickness from the middle toward the end portions thereof and being formed so that the thickness of each tapered layer, as measured at any given point along the length of the ski, is substantially equal to the thickness of the companion tapered layer as measured at the same point along the length of the ski, each of said non-tapered layers being of uniform thickness from end to end and being relatively thin compared with the thicker portions of the tapered layers.
4. A four layer ski as set forth in claim 3 in which the tapered and non-tapered layers are alternately arranged so that one of the tapered layers constitutes the top layer of the ski while one of the non-tapered layers constitutes the bottom layer of the ski.

5. A four layer ski including two full length tapered layers and two full length non-tapered layers, said tapered layers gradually decreasing in thickness from the middle toward the end portions thereof and being formed so that the thickness of one tapered layer, as measured at any given point along the length of the ski is substantially exactly equal to the thickness of the companion tapered layer as measured at the same point along the length of the ski, each of said tapered layers consisting of a plurality of narrow strips or rails glued together in side by side relation and each of said non-tapered layers being of one piece construction and of a thickness which is substantially less than the thickness of the middle portions of the tapered layers.

6. A multiple layer ski in which all of the layers extend the full length of the ski, two of said

layers being tapered so that they decrease in thickness from the middle toward the end portions thereof, said tapered layers being also formed so that the thickness of one, as measured at any given point along the length of the ski, is substantially exactly equal to the thickness of the other as measured at the same point along the length of the ski, the non-tapered layers being of substantially uniform thickness from end to end.

10 7. A multiple layer ski as set forth in claim 6 in which each non-tapered layer is of one piece construction and in which each tapered layer is composed of narrow lengthwise extending strips or rails glued together in side by side relation and is sandwiched in place between two of the non-tapered layers.

ALEXIS D. ANDREEF.
